UNITED STATES PATENT OFFICE

2,171,311

EAR AND MOUTH TELEPHONE ATTACHMENT

Joseph Moses, Toronto, Ontario, Canada

Application January 9, 1939, Serial No. 249,951

1 Claim. (Cl. 2—206)

My invention relates to a device in the nature of a partial facial mask adapted to engage over the mouth and lower portion of the face and loop over the ears for retaining in position.

5 The device may be formed or stamped from metal or any suitable fibrous material, and in shape adapted to conform with the contour of the lower portion of the face, with means formed therewith for readily looping over the ears, to attach for using.

10 An object of the device is for the purpose of eliminating surrounding noise when using the device such as in factories and other places where excessive noises occur, also in households where 15 a radio is in use.

The device is also an aid to those with defective hearing.

In describing the invention references will be made to the attached drawing in which:

20 Figure 1 is a view of a person's head with the device attached, and

Figure 2 is a perspective view of the device.

In the drawing, A designates a band shaped to conform with the contour of the mouth and 25 lower portion of the cheeks of a person's face.

The band terminates in ear loops, C—C adapted to loop over the ears for readily attaching and removing.

30 Cemented or otherwise secured on the inside of one of the ear loops C is a textile pad c to act as a muffler to tend towards preventing noises from reaching the ear, while the opposite ear is being used by an ordinary ear phone.

Secured to the ear loop C on the side of the head used for the ear phone, is secured a textile pad d formed with an aperture e to provide for an unobstructed concentrated passage to the ear.

5 Formed in the centre of the band A, in a position opposite to the mouth, is an aperture f, for the purpose of facilitating the wearer of the device for readily and unobstructedly speaking into the mouthpiece of the phone.

Around the border of the aperture f is cemented a textile band g to concentrate and moderate the voice of the user when speaking through the aperture.

10 Modification may be made in the shape and construction of the device, without deviating from the nature of my invention.

15 What I claim as my invention is:

In a device of the class described, a band formed and adapted to engage with the contour 20 of the lower portion of the face, loops formed on the terminals of said band, said loops adapted to engage over the ears of the wearer for maintaining the device in position, textile pads secured over a portion of said loops, one of said 25 pads adapted to muffle noises to the ear, the other of said pads having an opening therein for the use of an ear phone, an aperture formed in the centre of said band for speaking into the mouthpiece of a phone, a textile band cemented around 30 the edge of said aperture for modulating the voice when passing through the aperture.

JOSEPH MOSES.
